United States Patent Office

Des. 232,051
Patented July 9, 1974

232,051

DRAFTING INSTRUMENT

Peter S. Hoagland, 18769 Saratoga,
Lathrup Village, Mich. 48076

Continuation-in-part of design application Ser. No.
160,234, July 6, 1971. This application Dec. 15,
1971, Ser. No. 208,511

Term of patent 14 years

Int. Cl. D19—06

U.S. Cl. D52—6 A

FIG. 1 is a top perspective view of a drafting instrument showing my new design, the bottom thereof being plain and unornamented;

FIG. 2 is a right side elevational view thereof.

This is a continuation-in-part of design application Ser. No. 160,234, filed July 6, 1971.

I claim:

The ornamental design for a drafting instrument, as shown and described.
